[57] CLAIM

The ornamental design for a cord access grommet set for office furniture use, as shown and described.

DESCRIPTION

FIG. 1 is a perspective view of a cord access grommet set for office furniture use, as assembled, showing the top surface of the cap and base of my new design; FIG. 2 is an exploded perspective view showing the top surface of the cap and base; and

FIG. 3 is an exploded view of the cap and base taken from below and showing the side opposite that shown in FIG. 2.

FIG. 1

FIG. 2

FIG. 3
